SWITCH RAIL GUARD

Filed Aug. 4, 1923

2 Sheets-Sheet 2

UNITED STATES PATENT OFFICE.

FRANK C. ANDERSON, OF CINCINNATI, OHIO.

SWITCH-RAIL GUARD.

Application filed August 4, 1923. Serial No. 655,715.

To all whom it may concern:

Be it known that I, FRANK C. ANDERSON, a citizen of the United States, residing at Cincinnati, in the county of Hamilton and 5 State of Ohio, have invented certain new and useful Improvements in Switch-Rail Guards, of which the following is a specification.

My invention relates to switches, and its 10 object is to avoid derailments caused by objects wedged between diverging rails of a switch when dragged by passing trains; the present invention being an improvement on that disclosed and claimed in my Patent No. 15 1,414,767, issued May 2, 1922, and the especial object being to simplify the construction, installation and operation of such a device. Other objects will appear in the course 20 of the ensuing description.

I attain these objects by the device illustrated, for example, in the accompanying drawings, in which—

Figure 1 is a general perspective view of a switch with my invention applied thereto;

Fig. 2 is an enlarged side elevation of part of the stock-rail of the switch, and the guard mounted thereon;

Fig. 3 is a partial plan view of the same;

Fig. 4 is a vertical cross-section of the 30 same, on the plane of the line 4—4 of Fig. 2, intermediate parts of the operating shaft being omitted, but the outer end part thereof, with the outer crank thereon, being shown; and

Fig. 5 is a side elevation, looking from the track, of the two-piece convertible bell-crank.

The invention is illustrated as applied to a point-rail switch (Fig. 1) with right-hand turn-out, in which the left main-line rail is continuous, with the turn-out rail away therefrom when the switch is closed for main-line use as shown, and having the right-hand turn-out rail 1 continuous, with 45 the main-line point-rail 2 against this rail 1; the two point-rails being joined together by the brace-rods 3 and 4, with the rod 3, nearest the rail points, extending out and being connected to the switch-stand 5 by the connecting-rod 6, between the two head-blocks 7 which are extended out past the other cross-ties 8 to support the stand 5. The stock-rails being spiked to the ties, the point-rails slide to and from them on plates 55 9 fixed to the ties 7 and 8 and extending

under both stock-rail and point-rail, as usual.

On one of the ties, a suitable distance from the rail point, the two rails at the left have an elongated plate 10 corresponding to the other plates 9, extending out to the end of the tie 8 and having a bracket 11 riveted to it and extending up over the outer member of the base of the stock rail 1 with a head 12 against the outer side of the web of this rail; and having another bracket 13 riveted to it next to its outer end, with a head 14 alined with the head 12 of the bracket 11. The operating shaft 15 is journaled in these heads 12 and 14 and extends in through an opening in the web of the rail 1 and has pinned and keyed to it in between the rails 1 and 2, the crank 16; while on its outer end, out past the bearing 14, it has secured on it by means of a screw-key, the crank 17.

On the next tie 8, beyond the above described mechanism from the rail points, the plate 9' corresponding to the plates 9 of the other ties has riveted to it a bracket 18 with a head 19 in against the outer side of the stock-rail 1 similarly to the bracket 11, with a stud bolt 20 passed through an opening in the web of the rail 1, having a collar 21 fixed on it against the inner side of this web, and a nut 22 screwed on it against the outer end 80 of the bracket head 19, firmly securing the stud-bolt and the rail and bracket together. This stud bolt has on its inner end, spaced from the collar 21, the head 23.

The guard element 24 is an elongated 90 body, preferably of malleable cast iron, tapering to conform approximately with the adjacent sides of the heads of the rails 1 and 2, spaced an easy working distance therefrom. This element 24 is made long enough 95 to fill the space between the rails sufficiently, for such a distance that, at its narrower end, the space will be too narrow to catch the smallest object liable to wedge open the switch if dragged between the rails 1 and 2. 100 In these respects this element 24 is like that of my prior patent before mentioned. However, it differs therefrom, not only in the manner of its mounting, but in the shape of its upper surface which is to receive the objects dragged, and fend them up and out from between the rails 1 and 2.

At its narrower end, this element is flat on top, from which it has a slight bend; the succeeding part having on top the ridge 25, 110

widest and lowest near said bend, and highest and narrowest at its opposite end. This ridge 25 is succeeded by a channel part 26 gradually increasing in depth out to the opposite end of the element, where the bottom of the channel terminates in a curve 27 presenting a convex surface upward and outward from this end of the element, between the sides of the channel 26, which form lips 28 to lie under the heads of the rails 1 and 2 while the part with the ridge may incline up between the heads, with the narrow end part having its top about even with the tops of the rails. This is the guarding position 15 of the element.

To hold this element 24 in this position, yet allow it to move down out of the way of the car wheel flanges passing along the turnout rail, the element has the ears 29 on 20 its bottom just under the bend before mentioned, by which it is pivoted to the upper end of the crank 16; and this element has, under the channel part 26 near its opposite or wide end, an ear 30 having an elongated 25 slot 31 through which is received the stud bolt 20 with the ear between and guided by the collar 21 and head 23 thereof. This slot is so located and proportioned that it has the bolt 20 at its inner end when the element is raised by the crank 16; but when the crank 16 swings down in the direction of the arrow in Fig. 2, the element is slid on the bolt 20 until the bolt occupies the other 30 end of the slot. The ridge 25 is about as wide as the element at its low end; which part of the element will be depressed sufficiently below the rail top. The narrow high end of the ridge is far enough from the two rails 1 and 2 to escape the flanges of the car 35 wheels; and it is inclined down toward the low end of the guard element, to fend the object upward onto its top from the lower channel part 26. The lips 28, extending under the rail heads, prevent the object catching 40 under either head by sliding sidewise upon engagement with the curved end 27 which fends the object initially onto the guard element.

The crank 16 is operated automatically by 50 the switch mechanism through the medium of the connecting rod 32 having a fork connecting it to the lower end of the outer crank 17 below the tops of the ties; this rod extending slightly upward (Fig. 1) over 55 the ties, and having a fork on its opposite end connecting it to one arm 33 of the bell-crank fulcrumed on the upright pivot 34 in the bracket 35 fastened on the inner side of the nearer head-block 7 by a lug 36 overlying 60 the tie and permitting the bracket to stand partly below and partly above the tie or head-block with the above mentioned arm of the crank extending over toward the rails and swinging along the track. The lower 65 arm 37 of this bell-crank extends along the

track over toward the farther head-block 7, and swings across the track; having the outer end of the connecting rod 38 connected to it by the fork 39. This second connecting rod extends in under the track rails 1 and 2, with a fork 40 on its inner end, by which it is connected to the bracket 41 on the brace-rod 3. These arms 33 and 37 of the bell-crank preferably are made detachable, with a clutch connection 42 between 70 their hubs around the pivot 34 (Fig. 5) so that they can be differently relatively positioned in the crank if they are to be used for a left-hand turn-out instead of the right-hand turn-out as here shown, in which case 75 the crank and other details would be at the opposite side of the track, requiring a change of 180° in relative position of the upper and lower arm. The other parts all are interchangeable from right to left turn-out. 80

With the parts connected as just described, it will be seen that when the point rail is thrown to the left away from the stock rail, the bell-crank is swung so that the rod 32 90 pushes on the crank 17 in the direction of the lower arrow in Fig. 2, swinging the crank 16 down as indicated by the upper arrow, since both cranks are fixed on the shaft 15. Thus, the end of the element 24 95 which has been raised, is pulled down far enough to avoid contact of the wheel flanges therewith, which would result in breakage of the guard. Then when the switch is closed again, pulling the point rail back to 100 the stock rail, for main line travel, the rod 32 pulls on the crank 17, swinging the crank 16 upward and raising the adjacent end of the element to guarding position again. In my prior patent before mentioned, provision 105 is made for raising both ends of the guard, and lowering them; but by the provision of the ridged element, the ridge 25 is made to function sufficiently in place of the raised other end of the guard, and yet be sufficiently out of the way when the guard element is lowered. By raising and lowering one end of the guard only, the mechanism 110 may be much simplified, as exemplified herein, so that the device is less expensive to 115 make and install, as well as less liable to derangement in service. The brackets 11 and 13 on the tie plate 10, by which the device can be supplied to the trackmen in a more 120 fully assembled condition, also contribute to the above results; as does the bracket 18 on the plate 9 to some degree.

Variations in structure, proportions, operations and uses are possible; and therefore, while I prefer certain constructional details 125 and have disclosed these rather specifically to make clear my invention, as is required, I do not wish to be understood as being limited to such precise showing and description, but having thus fully described my in- 130

vention, what I claim as new and desire to secure by Letters Patent is:

1. An elongated tapered guard element to occupy the space between diverging rails 5 of a switch, one of said rails being movable, and means articulately connected to said movable rail to hold said element with the top of one end part substantially in the plane of the tops of said rails or to move 10 said element until said top is a substantial distance below said rail tops.

2. An elongated tapered guard element to occupy the space between diverging rails of a switch, and means to hold said element 15 with the top of one end part substantially in the plane of the tops of said rails and the other end part a substantial distance below said rail tops, or to swing said element until 20 said top is a substantial distance below said rail tops and slide the other end during the swinging.

3. An elongated tapered guard element to occupy the space between diverging rails of a switch, and means to movably hold 25 said element with the top of one end part substantially in the plane of the tops of said rails and the other end part a substantial distance below said rail tops, said element having a ridge along its top between 30 said end parts, with its top substantially in the plane of the rail tops when said element is up, but spaced away from one of said rails near the lower end of the element, to escape the wheel flanges traveling 35 along the rail.

4. An elongated tapered guard element to occupy the space between diverging rails of a switch, and means to movably hold 40 said element with the top of one end part substantially in the plane of the tops of said rails and the other end part a substantial distance below said rail tops, said element having said other end part channel shaped, with the sides of the channel under 45 the rail heads.

5. An elongated tapered guard element to occupy the space between diverging rails of a switch, and means to movably hold said element with the top of one end part substantially in the plane of the tops of said rails and the other end part a substantial distance below said rail tops, said element having said other end part channel shaped, with the sides of the channel under the rail 50 heads and with the bottom of the channel curved down at the end of the element.

6. An elongated tapered guard element to occupy the space between diverging rails of a switch, and means to movably hold said 60 element with the top of one end part substantially in the plane of the tops of said rails and the other end part a substantial distance below said rail tops, said element having said other end part channel shaped, with the sides of the channel under the rail 65

heads, and having a ridge along its top between said end parts, with its top substantially in the plane of the rail tops when the element is up, but spaced away from one of said rails near the lower end of the element, to escape the wheel flanges traveling 70 along the rail.

7. An elongated tapered guard element to occupy the space between diverging rails of a switch, and means to movably hold said 75 element with the top of one end part substantially in the plane of the tops of said rails and the other end part a substantial distance below said rail tops, said element having said other end part channel shaped, with the sides of the channel under the rail 80 heads and with the bottom of the channel curved down at the end of the element, and said element having a ridge along its top between said end parts, with its top substantially in the plane of the rail tops when the element is up, but spaced away from one of said rails near the lower end of the element, to escape the wheel flanges traveling 85 along the rail.

8. An elongated tapered guard element to occupy the space between diverging rails of a switch, and means to hold said element with the top of one end part substantially in the plane of the tops of the rails or to swing said element until said top is a substantial distance below said rail tops, the other end of the element being a substantial distance below the rail tops and having an ear on its bottom with a transverse slot, and means projecting from one of the rails into said slot, whereby this end of the element may slide during the swinging.

9. A guard element, means for mounting said element between diverging rails of a switch, and a channel at one end of said element with its sides under the rail heads and having its bottom curved down at this end of the element.

10. A guard element, and means for mounting said element to move one end thereof up and down between diverging rails of a switch and to hold the other end thereof down a substantial distance below the tops of the rails at all times.

11. A guard element, and means for swingingly mounting one end part of said guard element and slidably mounting the other end thereof between diverging rails of a switch.

12. An elongated tapered guard element to occupy the space between diverging rails of a switch, having a ridge along its top, wider and lower next to the narrow end of the element than it is next to the wide end of the element.

13. An elongated tapered guard element to occupy the space between diverging rails of a switch, having its wide end channel shaped with the sides of the channel pro-

jecting upward and outward from the bottom thereof and this bottom curved down at the end of the element.

14. An elongated tapered guard element 5 to occupy the space between diverging rails of a switch, having a ridge along its top, wider and lower next to the narrow end of the element than it is next to the wide end of the element, and having this wide end 10 channel shaped with the sides of the channel projecting upward and outward from the bottom thereof.

15. An elongated tapered guard element to 15 occupy the space between diverging rails of a switch, having a ridge along its top, wider and lower next to the narrow end of the element than it is next to the wide end of the element, and having this wide end 20 channel shaped with the sides of the channel projecting upward and outward from the bottom thereof and this bottom curved down at the end of the element.

16. A guard element to occupy the space 25 between diverging rails of a switch, one of which rails being movable, a swinging arm connected to said element, a shaft connected to said arm for swinging said arm, to extend along the top of one of the cross-ties of the switch, past the end of the tie, a 30 crank fixed on said shaft for swinging along the end of the tie, a rod pivoted to said other tie with one arm pivoted to said rod, and a second rod pivoted to a second 35 arm of said bell-crank, said second arm being offset downward from the first arm for connection to said second rod below the level of the tops of the ties, and said second 40 rod being adapted to connect to a part that moves when said rail is moved.

17. A guard element to occupy the space 45 between diverging rails of a switch, one of

which rails being movable, a swinging arm connected to said element, a shaft connected 45 to said arm for swinging said arm, to extend along the top of one of the cross-ties of the switch, past the end of the tie, a 50 crank fixed on said shaft for swinging along the end of the tie, a rod pivoted to said crank to extend up over another cross-tie of the switch, a bell-crank fulcrumed on said other tie with one arm pivoted to said rod, and a second rod pivoted to a second 55 arm of said bell-crank for connection to a part that moves when said rail is moved, said second arm having a clutch connection with the first arm of the bell-crank, so that said arms may be differently relatively positioned for the purpose described. 60

18. In combination with a guard element to be moved up and down alongside a rail of a switch, and a crank with a shaft through said rail, said crank being connected to said element to move it up and 65 down, a bearing bracket for said shaft next to said rail, a second bearing bracket for said shaft spaced outward from the first bracket, and a plate to extend under the rail and along a cross-tie of the switch, said 70 brackets being attached to said plate ready for assembly with the shaft, and the plate being adapted to be secured to said tie.

19. In combination with a guard element to be moved up and down alongside a rail of 75 a switch, with one part of the element sliding along the rail, a bracket to be placed next to the side of the rail opposite from said element, and a stud to extend from said bracket through said rail, for the element to 80 slide upon, and a plate to lie under the rail and be secured to one of the cross-ties of the switch, said bracket being attached to said plate in correct position for assembly with the rail and said element.

FRANK C. ANDERSON.
